FOOD MIXER OR SIMILAR ARTICLE

Walter E. Moore, Belnор, Mo., assignor to Knapp-Monarch Company, St. Louis, Mo., a corporation of Delaware

Application March 15, 1952, Serial No. 18,924

Term of patent 14 years

(Cl. D44—1)

To all whom it may concern:

Be it known that I, Walter E. Moore, a citizen of the United States and a resident of Belnор, county of St. Louis, State of Missouri, have invented a new, original, and ornamental Design for a Food Mixer or Similar Article, of which the following is a specification, reference being had to the accompanying drawing, forming a part thereof, in which:

Figure 1 is a side elevation of a food mixer or similar article showing my new design; and

The dominant features of my design reside in the parts shown by solid lines on the drawings.

I claim:

The ornamental design for a food mixer or similar article, substantially as shown and described.

WALTER E. MOORE.
